(57) **CLAIM**

The ornamental design for a cooking pot including for camping as shown and described.

DESCRIPTION

1. Cooking pot, including for camping

1.1 : Perspective

1.2 : Top

1.3 : Exploded

The design is related to an elliptical pot with a lid; the pot and the lid have lines all around the outer surface in the shape of ripples parallel to the base; the ripple-shaped lines are indentations and ridges.

1 Claim, 3 Drawing Sheets
